(57) **CLAIM**

The ornamental design for carried image processor, as shown and described.

DESCRIPTION

FIG. 1 is a top plan view of carried image processor showing my new design;

FIG. 2 is a front elevational view of carried image processor showing my new design;

FIG. 3 is a rear elevational view of carried image processor showing my new design;

FIG. 4 is a right side elevational view of carried image processor showing my new design;

FIG. 5 is a left side elevational view of carried image processor showing my new design;

FIG. 6 is a bottom plan view of carried image processor showing my new design; and,

FIG. 7 is a three dimensional view of carried image processor showing my new design.
